PAUL PERRY, OF CLEVELAND, OHIO

IRONING MACHINE

Application filed May 3, 1932. Serial No. 608,943.

The device of the present invention is an ironing machine designed particularly for use in the manufacture of garments such as dresses and blouses, and has for its object to 5 eliminate basting by hand of the several parts of a garment before they are pressed preparatory to sewing them together.

In the manufacture of women's and children's garments such as waists, dresses, 10 blouses, skirts and the like, individual pieces of fabric are cut and sewed together and later are assembled with and sewed to other parts of the garment. The parts of the garment which are initially assembled are usually 15 pressed or ironed to the proper shape before being sewed to other portions of the garment. Often the individual parts of the garment are provided with folds, pleats and the like, and before pressing it has been necessary, heretofore, to baste the folds, pleats or 20 the like, or to pin them down so as to hold them to proper form while they are being pressed or ironed.

The device of the present invention has for 25 its object to provide a device for pressing or ironing such portions of a garment to the proper form without first basting or pinning the fabric.

Another object is to provide an ironing 30 machine of simple and inexpensive construction suitable for the operation above referred to.

A further object is to provide an ironing machine provided with means for holding 35 the fabric to the form to which it has been folded by the operator prior to the engagement of the ironing shoe with the fabric.

A further object is to provide convenient 40 means for controlling the pressure exerted by the presser shoe on the material being ironed in order to prevent improper feed of the material, which would distort or disarrange the material in the folds during its passage through the machine.

45 With the above and other objects in view the invention may be said to comprise the device as illustrated in the accompanying drawing hereinafter described and particularly set forth in the appended claims, together 50 with such variations and modifications there-

of as will be apparent to one skilled in the art to which the invention appertains.

Reference should be had to the accompanying drawing forming a part of this specification, in which:

55 Figure 1 is a front elevation of the machine;

Fig. 2 is a side elevation of the machine;

Fig. 3 is a section taken on the line indicated at 3—3 in Fig. 1;

Fig. 4 is an end elevation viewed as indicated by the line 4—4 in Fig. 1;

Referring to the accompanying drawing, the machine of the present invention is provided with a frame 1 which has a top 2 which provides a support for the ironing elements and their actuating means. Upon the top 2 there is mounted a pair of spaced bearing standards 3 in which the ends of the shaft 5 of the roll 4 are journaled. Rearwardly of the roll 4 and parallel therewith a short distance below the level of the axis of the roll, there is supported a horizontal shaft 5 upon which is pivotally mounted presser shoe 6.

70 A presser shoe 6 is secured to the upper end of an arm 7 of a bell crank lever which is pivoted on the shaft 5, the lever being provided with a rearwardly extending arm 8 through which it is actuated to swing the

75 presser shoe toward or away from the roll 4. The presser shoe is preferably detachably secured to the arm 7, the arm 7 being provided with lateral flanges 9 to which the shoe

80 10. The presser shoe is a hollow member which contains an electrical heating element 11 located closely adjacent the forward wall of the shoe

85 which is formed to provide a concave face 12 of a curvature to conform to the roll 4. The presser shoe 6, however, differs from the conventional ironing or presser shoe in that the forward edge of the face portion curves upwardly away from the roll on a very short radius, as indicated at 13, in order to prevent

90 95 seams from rolling as the portion of the garment being pressed is brought into engagement with the shoe. The ironing shoe differs further from the conventional ironing shoe in that the heating element 11 is so arranged within the shoe as to concentrate 100

the heat largely in the forward edge portion of the shoe so that the edge of the shoe which first engages the material being pressed is the hottest portion of the shoe. This may be 5 accomplished by spacing the heating coils closer together within the forward portion of the shoe as shown in Fig. 3. In pressing pleats, folds and the like, in portions of a garment it is highly important that definite 10 creases be immediately formed in the fabric as the pieces are fed into the space between the presser shoe and roll so that the creases and folds will be formed along the desired lines. This is accomplished by the device of 15 the present invention by delivering the material directly into engagement with the hottest portion of the presser shoe.

Means is provided by which the presser shoe 6 can be instantly disengaged from the roll 4 whenever desired so that the pressure exerted by the presser shoe against the material passing between the roll and shoe can be regulated during an ironing operation. The shoe is moved about its pivotal support 20 by means of actuating connections from a rock shaft 14 extending from the front to the rear of the frame beneath the top 2, the shaft 14 being journaled in suitable bearing brackets 15 secured to the under side of the 25 top 2. A laterally projecting arm 16 is fixed to the shaft 14 adjacent its rear end and the outer end of the arm 16 is connected to the outer end to the bell crank arm 8 by means of a link 17. The shaft 14 has a second arm 30 18 fixed thereto and extending laterally in the same direction as the arm 16 and to the outer end of the arm 18 there is connected a link 19 which extends downwardly to a pedal 20 which when depressed by the foot 35 of the operator turns the rock shaft 14 in a direction to exert a downward pull on the link 17 to rock the ironing shoe outwardly away from the roll. The shaft 14 also has a downwardly extending arm 21 to which is 40 connected a coil spring 22 which extends horizontally from the lower end of the arm 21 to the inner end of an adjustable rod 23 which is anchored at its outer end to a supporting leg of the frame by means of a nut 45 24 which may be adjusted to regulate the tension of the spring. The shaft 14 has a second downwardly extending arm 25 fixed thereto and, adjustably mounted on the arm 25, there is a knee plate 26 which is carried by a collar 50 27 slideable on the arm 25 and secured in adjusted position thereon by means of a set screw 28 carried by the collar. A cam 29, provided with circumferentially spaced notches 30, is mounted on the shaft 14 and 55 60 cooperates with a spring pressed detent 31 for releasably holding the rock shaft 14 at its opposite limits of movement, in one of which the presser shoe is retained in retracted position and in the other of which it is retained in engagement with the roll. The

presser shoe is yieldingly pressed against the roll 4 by means of the spring 22, but in order to maintain a proper feed of the material it may be desirable to partially relieve the pressure at times during an ironing operation. This the operator can do by pressing laterally with his knee against the knee plate 26 or by exerting a pressure with his foot on the pedal 20, thereby exerting a torsional thrust on the rock shaft 14 in opposition to the thrust of the spring 22, taking a portion of the thrust of the spring with his knee or foot so that the presser shoe will be yieldingly pressed with a lighter thrust against the ironing roll. The operator can thus readily control the amount of pressure exerted on the work while it is passing beneath the presser shoe, and if at any time the work begins to move out of proper position, by simply increasing the pressure of his foot or knee can instantly disengage the presser shoe. 75 80 85

The ironing roll is driven by an electric motor 32 which is preferably a variable speed motor provided with a suitable control by which the speed may be varied as desired during operation of the machine. The drive from the motor 32 through the ironing roll 4 is through a suitable worm gearing in housing 33 which drives a belt 34 extending to a pulley 35 supported by a bracket 36 depending from the top 2. Mounted coaxially alongside the pulley 35, there is a second pulley 37 which is driven from the pulley 35 through a clutch of conventional design. A belt 38 90 95 provides a driving connection from the pulley 37 to a pulley 39 on an end of the shaft of the roll 4. Pulleys 35 and 37 are engaged and disengaged by a suitable clutch shifter lever 40 pivoted to the bracket 36. The lever 40 is provided with a projecting brake arm 41 which extends over the pulley 35 and engages with a cylindrical portion 42 of the pulley 37. The lever 40 has a laterally extending arm 43 which is connected by a link 44 to a foot pedal 45 so that the operator may, by means of the foot pedal, instantly disengage the clutch at any time and simultaneously apply the brake to stop the rotation of the ironing roll. 100 105 110 115

A feed table 46 is supported on the bearing standards 3 and overlies the ironing roll forwardly of the presser shoe, the inner edge of the feed table being closely adjacent the ironing roll, the presser shoe being positioned over the upper portion of the roll rearwardly of the axis thereof and the feed table being positioned over the upper portion of the roll forwardly of the axis. 120

The ironing of portions of garments which have folds, pleats or the like without previously basting or priming the folds or pleats, requires that the article be correctly folded or pleated as it enters between the presser shoe and ironing roll. The operator can 125 130

make the necessary folds or pleats in the fabric on the feed table 46 but it is difficult for the operator to hold the fabric to the proper form while it passes over the top of the ironing roll and into engagement with the presser shoe. This would also necessitate holding the fabric with the hand while it is passing over the top of the roll which would bring the hands of the operator uncomfortably 5 close to the hot presser shoe, with the danger that the operator might get his fingers caught between the shoe and roll. This difficulty is avoided in the machine of the present invention by providing a small roller 47 extending 10 the full length of the ironing roll and engageable with the top of the ironing roll between the feed table and ironing shoe. The roller 47 is mounted for vertical movements 15 toward and away from the ironing roll and is 20 preferably interconnected with the shoe shifting mechanism in such manner that it is engaged with the ironing roll as the presser shoe is moved away from the ironing roll and is shifted out of engagement with the ironing 25 roll as the presser shoe is moved into engagement with the ironing roll.

As herein illustrated the roller 47 is journaled in the forward end of a pair of arms 48 which are fixed to the horizontal shaft 5 upon 30 which the ironing shoe is pivoted. The shaft 5 is provided with a rearwardly extending arm 49 which is connected by a link 50 to an arm 51 fixed to the shaft 14 and extending to the side of the shaft 14 opposite that upon 35 which the shoe actuating arm 16 lies, so that the movement of the roller actuating link 51 is always in a direction opposite that of the shoe actuating link 17. With the ironing shoe disengaged from the roll and the roller 40 47 engaging the top of the ironing roll, the operator may fold the piece to be ironed to the proper form on the feed table 46 and feed the piece forwardly onto the ironing roll 4 and beneath the roller 47. The roller 47 serves 45 to hold the piece to be ironed against the top of the roll to retain the folds which have been made therein by the operator. When the forward edge of the piece has been advanced to a position where it will be engaged by the 50 forward edge of the ironing shoe, the ironing shoe is shifted into engagement with the roll, the roller 47 is lifted out of engagement with the work.

It will be apparent that the device of the 55 present invention provides a simple and inexpensive ironing machine which can be effectively used for pressing or ironing folds, pleats or the like in parts of garments during the process of manufacture without the necessity of hand basting or pinning the fabric prior to the pressing operation and in which means is provided to hold the pieces to be pressed flat against the roll while being delivered to the heat and pressure applying element, thereby very greatly lessening the dan- 60

ger of the operator injuring his hands in feeding the pieces beneath the heated presser shoe.

Furthermore, it is to be understood that the particular form of apparatus shown and described, and the particular procedure set 70 forth, are presented for purposes of explanation and illustration and that various modifications of said apparatus and procedure can be made without departing from my invention as defined in the appended claims. 75

What I claim is:

1. In an ironing machine, a roll, a presser shoe engageable with the roll and mounted for movement toward and away from the roll, a roller in advance of the forward edge 80 of the shoe mounted for movement into and out of engagement with the roll, and means for shifting the shoe out of roll engaging position and for simultaneously shifting the roller into roll engaging position. 85

2. In an ironing machine, a roll, a feed table at the front of the roll closely overlying the upper portion of the roll, a presser shoe overlying the upper portion of the roll rearwardly of the table, a roller above the 90 roll between the table and shoe, and means for simultaneously moving the roller and shoe in opposite directions with respect to the roll.

3. In an ironing machine, a roll, a presser shoe engageable with the upper portion of the roll rearwardly of its axis, a movable work engaging member in advance of the shoe mounted for movement toward and away from the roll, and means for simultaneously shifting the shoe into roll engaging position and for shifting said member away 95 from the roll. 100

4. In an ironing machine, a roll, a presser shoe engageable with the roll, a roller in advance of the forward edge of the shoe extending the full length of the shoe and parallel with the roll, said roller being mounted for movement into and out of roll engaging position, and a common actuating means 105 for the shoe and roller for simultaneously shifting one to roll engaging position and the other out of roll engaging position.

5. In an ironing machine, a roll, a presser shoe pivotally supported at the rear of the roll and movable into and out of engagement with the roll, a pair of arms pivoted rearwardly of the roll and extending past the ends of the shoe, a roller carried by said arms forwardly of the shoe, and means for simultaneously swinging the shoe and arms in opposite directions to move the shoe into and the roller out of roll engaging position or the shoe out of engaging position and the roller 115 into engaging position. 120

6. In an ironing machine, a roll, a presser shoe pivotally supported at the rear of the roll and movable into and out of engagement with the roll, a pair of arms pivoted rearwardly of the roll and extending past 130

the ends of the shoe, a roller carried by said arms forwardly of the shoe, means for simultaneously swinging the shoe and arms in opposite directions to move the shoe into and the roller out of roll engaging position or the shoe out of engaging position and the roller into engaging position, and a feed table having its inner edge closely adjacent the roll forwardly of the roller.

10 In testimony whereof I affix my signature.
PAUL PERRY.
